UNITED STATES PATENT OFFICE.

JASPER R. DRUMMAN AND TONY MIECZEJESKI, OF ROSEMONT, WEST VIRGINIA.

AEROPLANE SAFETY DEVICE.

1,371,203.

Specification of Letters Patent.

Patented Mar. 8, 1921.

Application filed November 8, 1920. Serial No. 422,591.

To all whom it may concern:

Be it known that we, JASPER R. DRUMMAN and TONY MIECZEJESKI, citizens of the United States of America, residing at Rosemont, in the county of Taylor and State of West Virginia, have invented new and useful Improvements in Aeroplane Safety Devices, of which the following is a specification.

- 10 The object of the invention is to provide a parachute or buoying attachment for emergency use in connection with aeroplanes and similar crafts, designed under normal conditions to be housed in an inconspicuous and 15 unobtrusive relation to the body of the car in position for momentary extension into operative position to sustain or buoy the craft in the event of injury to the propelling or supporting mechanism thereof, to the end that 20 should the normal flying mechanism of the car fail to operate while the craft is in the air, the safety appliance may be utilized to sustain the car or modify the rate of descent under conditions enabling the operator to 25 retain control thereof and thus effect a safe landing; and with this object in view the invention consists in a construction, and combination of parts of which a preferred embodiment is shown in the drawings, wherein:
- 30 Figure 1 is a plan view of an aeroplane provided with a safety appliance embodying the invention.

Fig. 2 is a longitudinal sectional view of the same showing in full lines the balloons in their extended or inflated position and in dotted lines in their folded or normal position.

Fig. 3 is a detail sectional view showing the manner of connecting the gas bags to the 40 nozzles of the distributing pipe.

Fig. 4 is a plan view of the clamp by means of which the connection between the gas bags and the gas distributing nozzles is effected.

45 The appliance consists essentially of a battery of three or more inflatable bags or balloons of which two are shown in the drawing respectively at 10, 11 and 11' arranged respectively fore and aft of the operator's station which is indicated at 12, and designed to be so positioned with reference to the body of the car as to afford a substantial support for the same when inflated or extended as indicated in Fig. 2, said

inflatable bags or balloons being preferably 55 of the inverted conical form shown and arranged in cylindrical seats 10^a, 11^a and 11^b; together with means whereby when, required, gas or suitable inflating fluid or vapor may be supplied to the bags or balloons to 60 reinforce them from their normal folded positions within the seats into the extended or inflated form affording a displacement sufficient to either support the car or carry a 65 sufficient portion of the weight thereof to enable the operator to maintain the equilibrium of the craft while making a descent and landing.

In the construction illustrated there is 70 provided a reservoir 13 preferably consisting of a plurality of chambers or compartments 13^a and 13^b connected by an equalizing pipe 14 for maintaining an equal pressure in both compartments and arranged in balanced 75 relation to the longitudinal axis of the body of the car, and a compressor 15 of any suitable mechanical construction connected by a feed pipe 16 with the reservoir and preferably obtaining a supply of gas with which 80 to charge the reservoir from an exhaust chamber 17 with which communicates the exhaust pipe 18 of the motor 19 by which the propeller 20 of the car is actuated. The gas under pressure is fed from the reservoir 85 to the gas bags or balloons by means of a supply pipe 21 provided at a point adjacent to the operator's station 12 with a controlling valve 22 and communicating with a distributing pipe 23 leading to nozzles 24 90 located in the apexes or lower ends of the balloon seats 10^a, 11^a and 11^b. These nozzles are preferably of conical form having rims 25 over which the mouths of the bags forming the balloons are extended and are secured by 95 bands 26 fitted with clamping bolts 27. Obviously when the buoyant effect of the safety appliance is desired, the reservoir having been properly charged to the desired pressure by the compressor, it is only necessary 100 for the operator to open the valve 22 in order to inflate the balloons and cause them without further manipulation or attention to assume an operative position, and as the extension of the balloons is upward from 105 the plane of the car it is obvious that they will serve to maintain the equilibrium of the latter whether the buoyant effect of the balloons is sufficient to support the car or is

merely sufficient to carry a portion of the weight while permitting the car to gradually descend under the steering control of the operator.

- 5 When it is desired to deflate the balloons the fluid contents thereof may be exhausted through the discharge pipe 28 communicating with an outlet pipe 29 fitted with a valve 30 which is also arranged within convenient reach of the operator's station.
- 10 The inflatable bag or balloon seats are of sufficient capacity to house the bags when not in use so that they do not project beyond the contour of the car and afford no obstruction to the progress of the car, but said seats serve to hold the bags or balloons in proper position for immediate inflation when required so that the safety appliance may be brought into operation momentarily when the emergency requiring their use arises, to thus afford the operator opportunity to either repair his mechanism and restore it to an operative condition or effect a safe landing at such a point as he may 25 select.

Having described the invention, what is claimed as new and useful is:—

In a safety appliance for aeroplanes and similar craft, the combination with the body of the same provided on its top with spaced cylindrical seats, of inflatable gas bags arranged in said seats, a gas storage reservoir, a valve controlled supply pipe connected with the storage tank, a distributing pipe connected with the supply pipe, conical shaped nozzles disposed in the bottoms of said seats concentric therewith and having rims over which the mouths of the gas bags are extended, the distributing pipe connecting with said nozzles, bands securing the mouths of the gas bags to said nozzles and provided with clamping bolts to effect firm engagement between the bags and the nozzles, and a valve controlled outlet pipe connected with the distributing pipe, as herein shown and for the purpose specified.

In testimony whereof we affix our signatures.

JASPER R. DRUMMAN.
TONY MIECZEJESKI.
